LONG-STROKE PUMPING JACK

Application filed April 16, 1928. Serial No. 270,536.

This invention relates to improvements in pumping jacks, and it consists of the constructions, combinations and arrangements herein described and claimed.

5 An object of the invention is to provide a pumping jack primarily intended for use in connection with oil wells, a particular attribute of the jack being the ease with which it may be unlimbered from its moorings for 10 temporary displacement preparatory to pulling the sucker rod should this become necessary.

Another object of the invention is to provide a counter weight for the reciprocating 15 chains, the provision of which includes an adjustable feature by which weight elements may be added or subtracted to suit different loads.

Other objects and advantages appear in 20 the following specification, reference being had to the accompanying drawings, in which

Figure 1 is a perspective view of the improved pumping jack,

Figure 2 is a side elevation, the superstructure being shown in a displaced position in dotted lines to facilitate the pulling of the sucker rod,

Figure 3 is a vertical section taken on the line 3—3 of Figure 2, parts being shown in 30 elevation,

Figure 4 is a detail horizontal section taken on the line 4—4 of Figure 2,

Figure 5 is a detail horizontal section taken substantially on the line 5—5 of Figure 2,

Figure 6 is a detail perspective view of the secondary chain grip.

In drilling oil wells it is often the case that productive strata will be encountered 40 under insufficient gas pressure to cause a voluntary flowing of the well. Such instances require the use of a pump, and usually the pumping power is applied to the pump plunger through an intermediary jack.

45 The lifting of considerable volumes of oil demands the movement of the pump plunger over sufficiently great distances to accomplish the purpose. In other words, a long stroke is preferable to a short stroke, and by 50 applying the invention to the need, the for-

mer constitutes an arrangement by which a long stroke may be supplied. The principle of the improved jack is such that a stroke of practically unlimited length may be applied to the well tool.

55 The foregoing general statement is subject to some qualification. It is not the jack that produces the stroke. The jack is an instrument through which a long stroke may be applied to the pump plunger. The means for producing the long stroke is known as a long stroke pumping power which is the subject of a companion application filed April 16, 1928, Serial No. 270,537, otherwise known as Case No. 2.

60 Reference is made to the drawings. A base, generally designated 1, carries a superstructure generally designated 2. It is upon the superstructure that a flexible element generally indicated 3, is movable. This element is respectively joined with a cable or rod 4 leading to the pumping power (not shown), and with a sucker rod 5. Regardless of the character of the cable or rod 4 this part is 65 herein known as the power element because by its instrumentality the power is transferred to the pumping jack.

70 The latter produces reciprocation for a tool in the well casing, the head of which is indicated at 6. The necessary reciprocation is produced by the reciprocation of the element 3. Although the latter runs over sprockets, as presently appears, it is regarded, nevertheless, as being reciprocable. It is through the reciprocation of the flexible 75 element 3 that the stroke of the sucker rod 5 is produced. Obviously the length of the stroke is limited only by the capacity of the pumping power, the height of the superstructure 2 and the length of the flexible element 3.

80 Longitudinal rails 7 and cross pieces 8 comprise the base 1. Usually these parts will be composed of channel beams. They are secured together to compose a rigid 85 rectangle, and bolts 9 or the like, are employed to fasten the base and the entire jack down.

85 The superstructure 2 comprises the following parts: a pair of beams 10 that are 90

perpendicular to the base, a top frame composed of parallel rails 11 and cross pieces 12, braces 13 between the beams 10 and rails 11, and rear struts 14. Bearings 15 on the beams 10 carry the shaft 16 of a pair of idler sprockets 17. Sets of bearings 18 on the top frame carry parallel shafts 19 which have pairs of idler sprockets 20 and 21.

It is the purpose of the top frame 11 to 10 overhang the well casing. The adjacent vertical component of the flexible element 3 is in line with the sucker rod 5. The stroke of the jack is thus in the direction of the axis of the sucker rod. There is no distortion of 15 either the vertical component or the sucker rod during the functioning of the jack. The stroke is directly in line with the sucker rod regardless of how long the former may be.

A plurality of hinge connections not only 20 serve to hold the superstructure 2 in rigid relationship to the base 1, but also permit the displacement of the superstructure when certain ones of the connections are unlubricated. These connections comprise knuckles 22 and 23 carried by the beams 10, and associated 25 knuckles 24, 25 carried by the base. These are connected by hinge pins 26 and 27. The elements 23, 25 and 27 may act as a hinge upon which the superstructure may be swung 30 to the right in Figure 2.

The elements 22, 24 and 26 may act as a hinge upon which the superstructure may be swung to the left in Figure 2. The latter swinging is a possibility but not a requirement. Usually the requirement is to swing 25 the superstructure to the right preparatory to pulling the sucker rod 5 should this become necessary. For that purpose the hinge pins 26 must be withdrawn. Should an instance occur in which swinging of the superstructure to the left becomes desirable, the hinge pins 27 would have to be withdrawn.

In either case the struts 14 must be released. These are connected with the base 45 by hinge pins 28 that fit pairs of knuckles 29 and 30 respectively on the struts and base. Pins 31 pass through the upper ends of the struts and pairs of ears 32 (Figure 4) on the beams 10. The pins 28 and 31 will form a lock when in position in the various knuckles, holding the superstructure rigid upon the base. Removal of the pins 31 will permit 50 swinging of the beams 10 and carried parts, provided one or the other of the sets 26, 27 is first removed. The struts 14 may be swung back out of the way.

The beams 10 serve as guides for a counter weight 33. This counter weight is composed of a plurality of weight elements. The 55 counter weight constitutes the connector between what are hereafter known as the primary and secondary components of the flexible element 3. The first comprises a pair of chains 34 that is trained over the idler sprockets 17. The second comprises a pair

of chains 35 that is trained over the pairs of idler sprockets 20, 21. The chains 34 are closer to each other than are the chains 35. This arrangement has the following advantage:

The driving power, being received by the primary component 34, may be applied substantially at the axis of movement of the counter weight 33. The chains 34 may therefore be disposed close together. But in order that there may be an equalized lift upon the sucker rod 5, and an equalized action in general, it is desirable to dispose the chains 35 a noticeable distance apart.

This various spacing of the chains 34 and 80 35 is facilitated by the construction of the counter weight to which the description now reverts. Lock bolts 36 secure the plurality of weight elements. The lower element carries a pair of leaves 37 between which the chains 34 are inserted prior to being secured by bolts or pins 38 that pass through the spaces between certain links. In practice one of the leaves 37 may be made integral 85 with the bottom element, and the other may merely constitute a loose follower plate to be held in place by the bolts or pins when applied.

Similar leaves 39 on the upper weight element receive the chains 35. Bolts or pins 40, passing through spaces between certain links, firmly hold the chains. Figure 3 makes it clear that the chains 35 are attached to the counter weight at points farther apart than those at which the chains 34 are attached. The counter weight 33 is intended to substantially counter balance the sucker rod 5 and its carried parts, thus lessening the amount of operating power required. This assemblage of the counter weight will permit the addition or subtraction of weight 100 elements.

A coupling 41 joins the cable or rod 4 with the chains 34. The coupling includes sets of bolts or pins 42 which pass through spaces between certain links. The coupling 41 constitutes the primary chain grip. A secondary chain grip comprises the yoke 43 shown in Figures 1 and 6. This yoke is made in two parts, and when these are bolted together at 105 44 the sucker rod 5 is intended to be firmly held by the central enlargement 45.

Upstanding arms 46 make direct connection with the chains 35. Teeth 47 on certain ones of the arms fit in the spaces between certain links of the chains thus to make a secure connection. Bolts or pins 48 complete the connection. These bolts pass through from one side to the other of the arms, and clamp the chains therebetween. Certain bolt holes 49 (Fig. 6) pass through adjacent teeth 47. The teeth and bolts combined make a connection that will not come apart in ordinary service.

Supplemental bracing may be employed in 110 115 120 125 130

practice. Such bracing may comprise guys 50 and a braced front strut 51. The former are anchored to the ground and to the beams 10 as shown in Figure 1, but the anchors are such that swinging of the superstructure to 5 the right will not be interfered with.

The front strut 51 may merely rest upon the flooring, the upper end being secured to 10 the top frame 11. The presence of this strut would prevent swinging of the superstruc- 15 ture to the left, and inasmuch as the latter swinging of the superstructure is a mere possibility and not a probability, it follows that the front strut may be employed in the construction under ordinary circumstances.

15 The operation is readily understood. Reference must be made to the companion patent application for the details of the pumping power in connection with which the improved jack is intended to be used. This 20 statement is not to be regarded as a limitation because the jack may be employed in connection with other powers.

Pulling and releasing actions of the cable 25 or rod 4 will result in a reciprocation of the flexible element 3 so that the suction rod 5 is moved up and down. The direction of movement of the rod will be rectilinear. The rod will not be subject to any curvature. As 30 the primary chain component 34 moves under the influence of the cable 4 the counterweight 33 will reciprocate in the guides defined by the perpendicular beams 10. The second component 35, being connected with 35 the counterweight, will transfer the power to the secondary chain grip 43 and so to the sucker rod 5. It has been explained already that the chains 34 are relatively close together so that the primary application of the power 40 is confined to the substantial axis of the counterweight 33. The chains 35 are spread considerably further apart, the result being an equalized action upon the sucker rod.

Should the occasion arise to swing the 45 superstructure 2 back into the dotted line position in Figure 2, it is only necessary to remove the hinge pins 26 and 31. The struts 14 can be swung back upon the hinge pins 28 out of the way. The rest of the superstruc- 50 ture may then be swung as far back as necessary. Nothing else will come apart, and said superstructure will move as a unit. Additions and subtractions of the weight elements to the counterweight 33 may be readily made 55 as already described.

While the construction and arrangement 60 of the improved pump jack is that of a generally preferred form, obviously modifications and changes may be made without de- 65 parting from the spirit of the invention or the scope of the claims.

I claim:—

1. A pump jack comprising a flexible element connectible with a sucker rod and with 70 a power element, a structure having idlers

over which the flexible element is trained so that one component hangs directly over the sucker rod, a movable mounting for the structure permitting swinging it, and a counterweight joined with the flexible element and 75 guided upon a part of the structure to sustain it in position and prevent independent swinging when the structure is swung.

2. A pump jack comprising pairs of chains that constitute the primary and secondary 75 components of a flexible element, a structure having idlers over which the chains are trained, means by which a power element is coupled to one end of the primary component, means riding upon a part of the structure, at 80 which the remaining end of the primary component is connected, and at which the ends of the chains of the secondary component are connected relatively far apart, and means by which the remaining ends of said chains 85 are coupled with a sucker rod at the same spacing to effect an equalization of the applied power.

3. A pump jack comprising a flexible element which includes pairs of chains that constitute primary and secondary components of a flexible element, a structure upon which said element is supported, sets of idlers over which the chains are trained, the primary chains being relatively close and the secondary chains being relatively far apart, coupling means by which the remote ends of the chain components are respectively connected with a power element and with a sucker rod, and means riding upon a part of the structure to 90 which the primary component is connected at the axial center, and to which the secondary component is connected at each side of said center.

4. A pump jack comprising a flexible operating element, a structure having idlers over which said element is trained, a base, and hinges connecting the structure with the base, including hinge pins that are removable to permit swinging the structure in either of two directions in respect to the base. 105

5. In a pump jack, a superstructure which has sets of hinge knuckles on opposite sides, a base which has corresponding hinge knuckles, and pins fitted in corresponding knuckles to rigidly secure the superstructure upon the base, the pins on either side being removable to permit swinging of the superstructure in either of two directions. 110

6. In a pump jack, a superstructure having ears and hinge knuckles on opposite sides, a base having hinge knuckles corresponding with those of the superstructure and having other hinge knuckles, hinge pins connecting the first hinge knuckles being placed to either hold the superstructure rigid or permit swinging in either of two directions, struts having hinge knuckles co-acting with said other hinge knuckles, and hinge pins connecting said last hinge knuckles and the struts with 120

125

130

the ears, either holding the superstructure rigid or permitting said swinging when the hinge pins are removed from the ears and struts.

5 7. In a pump jack, a flexible operating element including chains, a two-part yoke securable upon a sucker rod, arms upon the yoke receiving the chains therebetween, teeth on certain ones of the arms fitting in spaces between certain chain links, and means securing the arms and extending through the spaces.

10 8. A pump jack comprising a flexible reciprocable element, a framework over which the element is guided including confronting channels, and a counterbalancing weight connected to said element being received by and guided in said channels.
